DUPLEX PUMP

Ben D. Barton, Adrian P. Adney, and Harold A. Bentley, Battle Creek, Mich., assignors to American-Marsh Pumps, Inc., Battle Creek, Mich., a corporation of Michigan

Application October 3, 1938, Serial No. 232,992

8 Claims. (Cl. 103—106)

This invention relates to improvements in duplex pumps.

The main objects of this invention are:

First, to provide a duplex pump suitable for fire apparatus and adapted to be operated selectively for single-stage or multi-stage operation.

Second, to provide a pump of the type described controlled and driven by a selective gear transmission well adapted to be connected with the drive for an automotive vehicle.

Third, to provide a duplex pumping system comprising a plurality of rotary centrifugal pump units or members having different pumping characteristics and means for selectively driving the same to function separately or in series.

Fourth, to provide a duplex pumping mechanism having a plurality of rotary pumps driven from a common drive and transmission and arranged to operate with a common suction and discharge.

Fifth, to provide a multiple-stage pump having novel provisions whereby the pumps thereof are adapted to be driven separately or in unison and whereby when either of the pumps is driven separately the other is automatically kept primed for instant operation when desired and to prevent freezing thereof.

Sixth, to provide a pumping mechanism of the type described and a novel arrangement for priming one of the pumps by means of the other.

Objects relating to details and economies of the invention will appear from the description to follow. The invention is defined in the claims.

A preferred embodiment of the invention is illustrated in the accompanying drawings, in which:

Fig. 1 is a fragmentary plan view partially broken away and in section illustrating one embodiment of the invention.

Fig. 2 is a view in side elevation partially broken away and in section illustrating certain of the features of the invention.

Fig. 3 is a fragmentary front view partially broken away and also in section on line 3—3 of Fig. 1, illustrating further details.

Fig. 4 is an enlarged fragmentary detail view in section on line 4—4 of Fig. 1.

Fig. 5 is an enlarged fragmentary view partially broken away and in section on line 5—5 of Fig. 2.

The present invention relates to a pumping system or mechanism which is particularly adapted for use in automotive fire fighting and general field or portable service pumping. The embodiment illustrated is designed to be driven

from the drive of a motor vehicle. One feature of the invention relates to provisions whereby the pumping system may be operatively connected to the drive shaft of the vehicle, there being means provided to selectively couple the rear axle of the vehicle with the transmission thereof in the usual manner or to disconnect the rear axle and couple the pumping mechanism with the vehicle transmission.

The pumping mechanism per se possesses several features of novelty which will be hereinafter described but may be broadly stated to consist of a plurality of independent rotary pumps of different pumping characteristics and means whereby the same may be selectively driven either independently of one another or together in staged or series relation, and automatic priming and freezing preventing provisions of great utility.

Referring to the drawings, the reference numeral 1 in Figs. 1, 2, and 3 generally indicates the pumping system or mechanism of the invention, which consists of a main suction header 2 adapted to be connected by suitable means such as a hose (not shown) with a source of water, for example, a hydrant, tank, or reservoir, a river, ditch, or the like. This main conduit leads through a branch 3 to the intake of a suitable large capacity rotary centrifugal pump of suitable type which is generally designated 4.

The pump 4 discharges into a valve housing 5, see Figs. 1 and 3, through a check valve 7, the valve of this embodiment being a gravity closed poppet type valve. The pressure of the discharge from the pump 4 serves to unseat the valve 7 as will be understood. The valve housing 5 communicates through a passage 8 with the discharge line which is designated by the reference numeral 9 and which will be connected to a suitable discharge hose or conduit.

There is arranged coaxially with the pump 4 in 40 a manner to be hereinafter described a second rotary centrifugal pump 10 which is of the high pressure type. The intake chamber 11 of this pump is connected through a pipe 12 and other suitable fittings with the main conduit 2, there being a check valve 13 inserted in the pipe 12 in the manner illustrated in Fig. 1, which will permit flow of fluid in the intake direction indicated by the arrow, but will prevent flow in the reverse direction.

The discharge 14 of the pump 10 leads to a valve housing 15, Fig. 2, through a port 16 controlled by check valve 17. The valve 17 of this embodiment is of the gravity actuated poppet type similar to the valve 7. The valve chamber 55

15 communicates through a fitting 18 with the discharge pressure of the pump 10 in a manner which will be apparent.

A by-pass is provided between the discharge of the pump 4 and the intake of the pump 10 for use when the pumps are being run together in staged or series relation. This by-pass is designated by the reference numeral 19 and consists of a pipe 20 and other suitable fittings communicating with the discharge of the pump 4 below the valve 7, as illustrated in Fig. 3, and a further pipe 21 communicating with the intake chamber 11 of the pump 10, as illustrated in Fig. 2. The pipes 20 and 21 are connected together through 15 a suitable check valve 22, a flap valve being shown in Fig. 1, the function of which will be referred to.

Pipe 21 communicates through a manually operable valve 23 with a water tank 24 or other source of water to be used in priming, as will be 20 hereinafter described, which in actual practice is arranged above pump 10 to cause a flow of water thereto by gravity when the tank is used. Other priming provisions in the system include a circuit consisting of a pipe 25 connected at 26 to the 25 discharge pipe 9, see Fig. 1. The pipe 25 is connected through a valve 27 and a suitable fitting or nipple 28 with an ejector chamber 29, as illustrated in Fig. 4, this chamber being communicated with the interior of the pump 4 and also 30 with a water and air exhaust line 30 leading back to the tank 24. A manually controlled valve 31 is placed in this line. The operation of the above described ejector for priming pump 4 when the 35 system is initially placed in operation will be apparent. When water is supplied under pressure from the line 9 and pump 10 through the pipe 25, the effect is to withdraw air from the pump 4 and thereby prime the same, the withdrawn air and the ejector water being returned to the tank 24 40 where they are separated.

The invention includes means whereby the pumps 4, 10 may be selectively driven separately depending upon the existent condition which must be met; i. e., either the high capacity or 45 volume of pump 4 may be availed of or the smaller capacity but higher pressure of the pump 10 may be used. Alternately, pumps 4 and 10 may be driven together in staged or series relation with the output of pump 4 supplied to the 50 intake 11 of the pump 10.

The aforesaid provisions whereby a proper drive for the selective operation of the pump is made possible and the provisions whereby the system is selectively coupled with the drive shaft of the 55 vehicle or other suitable drive shaft are clearly illustrated in Fig. 5. Referring to that figure, the reference numeral 32 designates a gear case interposed between the pumps 4 and 10, having bearing provisions therein for the respective 60 shafts 34 and 33 of pumps 4 and 10. Gears 35, 36 of smaller and larger diameter, respectively, are fixed to the shafts 33, 34. The automobile propeller shaft or other driving shaft is illustrated in dotted lines and indicated by the reference numeral 37. This shaft, in the embodiment illustrated, is connected to the automobile transmission in a well known manner and it extends into and has a suitable bearing 38 in a housing or case 39 secured to the gear case 32. The shaft 37 is splined for a considerable lengthwise distance 65 within the case 39 for a purpose to be described.

The housing 39 on the side thereof opposite the shaft 37 has an extension 40 secured thereto which is provided with bearings 41 for a rotary 70 clutch member 42 connected to the axle drive

shaft 43 illustrated in dotted lines. The clutch member 42 on its inner side has an annular flange 44 provided with internal teeth 45. These teeth 45 are adapted to mesh with a gear or pinion clutch member 46 integral with a gear 47 which 5 is slidable on the splined end of the shaft 37. The outermost end of the last named shaft is rotatably mounted in a bearing 48 carried by the clutch member 42. The gear 47 has the hub thereof grooved annularly at 49 to receive a shifter fork 50 for sliding the gear axially on the shaft 37 so that the clutch gear member 46 is engaged with or disengaged from the teeth 45, as will be understood.

The gear 47 serves as the primary drive member for the pumps 4, 10 from the shaft 37. It is selectively connected to the pumps through a cluster gear member generally designated 51 having a pair of integral gears 52, 53 of larger and smaller respective diameter adapted to mesh with the pump drive gears 35, 36 respectively. The arrangement is such that high pressure pump 10 is driven at a higher speed than high capacity pump 4 for a given engine speed. The gear cluster 20 may be adjusted to drive either pump independently or to drive them simultaneously, depending upon the lateral position of the gear member 51. The teeth of the gears 52, 53 are sufficiently wide and strong to permit this selective individual or combined engagement. The gear 52 is in mesh with the gear 47 when the pumps are to be driven.

The cluster gear member 51 is slidable axially of a splined jack shaft 54 mounted in suitable bearings in case 32 and the hub of the gear member 51 is annularly grooved to receive a shifter fork 55 whereby the lateral position of the member 51 may be manually controlled.

From the foregoing, it will be seen that by manipulation of the shifter fork 50, the transmission shaft 37 is drivingly connected to the axle when the clutch gear 46 is engaged with the teeth 45. At this time the gear 47 is out of mesh with the gear 52; however, when the parts are in the position illustrated in Fig. 5, the gear 47 is drivingly engaged with the gear 52. In the position illustrated, the cluster gear member 51 is arranged whereby the gear 36 and high capacity pump 4 are driven. To disconnect this pump and to drivingly connect the pump 10, it is necessary only to manipulate the shifter fork 55 to bring the gears 35, 52 in mesh, and as noted above both pumps may be driven by manipulating the gear member 51 to cause the respective gears 36, 53, and 35, 52 to mesh simultaneously. It will be understood that as cluster gear member 51 is shifted laterally as described the gear 47 is shifted therewith to keep gears 47, 52 in mesh. This simultaneous movement may be effected by means of suitable provisions (not shown) for connecting forks 50, 55 for movement in unison but permitting movement of gear 47 out of mesh with gear 52 when it is desired to disconnect the pumps from shaft 37.

Referring to Figs. 1, 2, and 3, when the pump 4 alone is driven, it discharges to pipe 9. At this time, the valves 23, 27, and 31 will be closed. During the operation of pump 4, the pump 10 is always kept primed, ready for instant operation if desired, by the flow of water from pump 4 through by-pass 19 and the flap valve therein to and through the casing of pump 4, thence to discharge 9. This fills the casing of pump 10 and maintains a circulation therethrough, enabling the same to be brought into instantaneous action 75

merely by shifting gear 52 into mesh with gear 35. The flow of water also prevents freezing of the pump in cold weather.

When the pump 10 alone is driven, it discharges to pipe 9, the discharge valve 7 of the pump 4 being then closed by the pressure of pump 10 and the valves 23, 27, and 31 being closed. At this time, the vacuum at the intake 11 is effective through by-pass 19 to induce a flow of water through the by-pass, hence through the casing of pump 4, from main header 2. This keeps pump 4 in primed condition and prevents possibility of its freezing. It will thus be seen that our invention provides a duplex pumping system wherein the pumps thereof automatically prime one another, once either thereof is placed in operation, without the manipulation of valves or other attention. A further result is that when pump 10 is running alone the intake chamber 11 is supplied from two sources, i. e., pipes 12 and 21, to insure delivery of an adequate volume thereto.

When it is desired to drive the pumps 4, 10 simultaneously in staged or series relation, the valves 23, 27, and 31 are closed. In such case, the pump 4 discharges through the by-pass 19, consisting of the pipes 20 and 21 and valve 22, into the intake chamber 11 of the pump 10. Pump 10 then impels the water past its valve 17 through fitting 18 to the discharge pipe 9. At this time, the pressure exerted below the same by the discharge from the pump 4 and accordingly the valve will remain closed. Furthermore, sufficient pressure will be built up in the pipe 12 to maintain the valve 13 closed, whereby the pump 10 will be supplied only from the pump 4.

By means of the structure described above, it is possible to prime the pump 4 by the jetting principle. In this case, the ejector valve 27 and the valve 31 in the return or exhaust line 30 are opened; likewise, the valve 23 is opened. The pump 10 thereupon takes water from the tank 24, forces the same to the pipe 9, thence through the pipe 25 and the ejector 29 to extract air from the pump 4. Valve 22 prevents reverse flow in by-pass 19 at this time. The water and extracted air are then returned to the tank 24 for separation. These priming instrumentalities are availed of only in initially priming pump 4 when commencing operations. Thereafter pumps 4 and 10 are self-priming, as described above.

It is to be understood that the term "rotary" is employed in the foregoing specification and in certain of the claims to follow in its broad sense, i. e., as distinguishing from the reciprocating type and not necessarily to designate a positive displacement rotating pump as contrasted to a centrifugal pump, but, on the contrary, to include both of the last named types.

The aforesaid system is exceedingly compact and efficient; it is convenient to mount on any automotive or other driving device; and it affords a considerable range of operating capacities or pressures without increasing the bulk of the system. Moreover, it primes itself automatically, rendering it instantly capable of any desired type of pumping or of changes from one type to another. These advantages are due to the use of a common drive for the two pumps, likewise a common suction and discharge, and further to the means for selectively bringing the pumps into operation whereby the pump having the correct desired operating characteristic is available.

We have illustrated and described our improvements in an embodiment which we have found very practical. We have not attempted to illustrate or describe other embodiments or adaptations as it is believed this disclosure will enable those skilled in the art to embody or adapt our improvements as may be desired.

Having thus described our invention, what we claim as new and desire to secure by Letters Patent is:

1. A duplex pump adapted to be mounted on an automotive vehicle and driven thereby, comprising a pair of rotary pumps of different characteristics adapted to be driven individually and independently of one another or as a unit, common supply and discharge means for said pumps, means for staging the pumps when they are driven as a unit comprising a by-pass connected to the output of one of said pumps and to the intake of the other thereof, the first-stage pump having a discharge valve to said common discharge subject to the difference in fluid pressure produced by said first- and second-stage pumps when the pumps are operated as a unit, a source of priming liquid, and means connected to said source and by-pass for initially priming said one of said pumps by the other and including hydraulic air evacuating means connected to said one of said pumps and actuated by the output of the other, said by-pass including means for preventing reverse flow therein to said one of the pumps during said initial priming.

2. A duplex pump comprising a pair of rotary pumps of different characteristics adapted to be driven individually or as a unit, common supply and discharge means for said pumps, and means for staging the pumps when they are driven as a unit and for maintaining the non-operating pump primed when one of the pumps is driven individually, comprising a by-pass connected to the output of one of said pumps in advance of the common discharge and to the intake of the other thereof, a pressure responsive valve in the by-pass yieldable to permit flow therethrough during staged operation, and priming means including a source of priming liquid connected to said by-pass between said intake and said valve, and a hydraulic air evacuating device connected to the output of said other pump and to the casing of said one of said pumps.

3. A duplex pump comprising a pair of pumps of different pressure characteristics adapted to be driven individually and independently of one another or as a unit, common discharge means for said pumps, a discharge valve for the lower pressure pump controlling the flow of liquid therefrom to said common discharge, and means for staging the pumps when they are driven as a unit, comprising a by-pass connected to the output of said lower pressure pump in advance of said valve and to the intake of the other pump, whereby during staged operation said valve is maintained closed due to the difference in pressure of the liquid in said common discharge maintained by the higher pressure pump and the discharge pressure of the lower pressure pump, and means for priming said first named pump including a source of priming liquid connected to said by-pass between the intake of the higher pressure pump and the casing of the lower pressure pump, said by-pass having a pressure responsive valve therein for preventing reverse flow of the liquid in the by-pass during priming.

4. A duplex pump comprising a high capacity rotary pump, a high pressure rotary pump, com-

- mon supply and discharge means for said pumps connected to the respective intakes and outlets thereof, said pumps being adapted to be driven individually or together whereby to effect staged operation thereof, means for connecting the discharge of said first named pump with the intake of said second named pump for staged operation, comprising a by-pass having a check valve therein, and means for initially priming said first named pump by means of said second named pump, comprising means for connecting said by-pass between said intake and check valve to a source of fluid supply, and a hydraulically actuated air evacuating device connected to the casing of the first named pump and to said common discharge, said check valve closing during initial priming but opening during individual operation of said pumps whereby to permit the same to prime one another.
- 20 5. A duplex pump comprising a first rotary pump, a second rotary pump, means for supplying fluid to the intakes of said pumps, said pumps being adapted to be driven individually or together whereby to effect staged operation thereof,
- 25 a by-pass having a check valve therein for connecting the discharge of said first named pump with the intake of said second named pump for staged operation, and means for initially priming said first pump by means of said second pump, comprising means for connecting the by-pass of said second pump to a source of fluid supply at a point between the valve and intake of said second pump, an ejector connected to said first pump whereby to extract air therefrom when the ejector is operated, and means for connecting the ejector with the discharge of said second pump to operate the same, said valve preventing reverse flow in the by-pass during priming, said by-pass permitting a flow of fluid through either one of said pumps when the other is being operated individually to prime the non-operating pump.
- 40 6. A duplex pump comprising a first pump, a second pump, means for connecting said pumps in series, and means for initially priming said first pump by means of said second pump, comprising means for connecting said first named means to a source of fluid supply, means to prevent reverse flow to said first pump during initial priming, an ejector connected to said first pump whereby to extract air therefrom when the ejector is operated, and means for connecting the ejector with the discharge of said second pump.

7. A pumping system comprising a rotary pump having relatively high capacity and low pressure in operation, a second rotary pump having relatively high pressure and low capacity in operation, said pumps being adapted to be driven individually and independently of one another or together as a unit whereby to effect staged operation thereof, common discharge means connected to the discharge of each of said pumps, and means for connecting said pumps for staged operation, comprising a by-pass continuously open while the system is pumping leading from the discharge of the first named pump to the intake of the second named pump and at all times permitting flow of liquid in the direction from said discharge to said intake, and a pressure actuated valve controlling the discharge of said first named pump to said common discharge, said by-pass being connected to the discharge of the first named pump on the side of the valve opposite said common discharge whereby during staged operation said valve is maintained closed by a difference in the forces exerted on opposite sides thereof arising from the different pressure characteristics of the pumps.

8. A pumping system comprising a pump having relatively low pressure in operation, a second pump having relatively high pressure in operation, said pumps being adapted to be driven individually and independently of one another or together as a unit whereby to effect staged operation thereof, common discharge means connected to the discharge of each of said pumps, and means for connecting said pumps for staged operation, comprising a by-pass continuously open while the system is pumping leading from the discharge of the first named pump to the intake of the second named pump and at all times permitting flow of liquid in the direction from said discharge to said intake, and a pressure actuated valve controlling the discharge of said first named pump to said common discharge, said by-pass being connected to the discharge of the first named pump on the side of the valve opposite said common discharge whereby during staged operation said valve is maintained closed by a difference in the forces exerted on opposite sides thereof arising from the different pressure characteristics of the pumps.
